UNITED STATES PATENT OFFICE.

OTTO H. VAN AMBURG AND LESLIE A. KEMPTON, OF BRIDGEPORT, CONNECTICUT,
ASSIGNORS TO GENERAL ELECTRIC COMPANY, A CORPORATION OF NEW YORK.

SAFETY SWITCH.

Application filed June 25, 1923. Serial No. 647,513.

The present invention relates to electric switches and more especially to safety switches. When electric power is utilized in industrial establishments for driving individual machines, it is desirable that the operator of the machine be enabled to start and stop it at will by closing and opening the electric circuit. On account of the danger of serious accidents occurring through ignorance, carelessness or curiosity on the part of an operative in coming in contact with an electrically charged part, it is customary in such power installations to provide safety switches for use in starting and stopping the machines. The characteristic feature of these switches is that all the electrically charged parts are locked up in a protective encasement with only the insulated operating handle accessible on the outside thereof.

The object of our invention is to provide an improved safety switch which shall be strong, compact, efficient in service, capable of standing rough usage, and of low manufacturing cost.

One embodiment of the invention is shown in the accompanying drawing in which Fig. 1 is a front elevation of our safety switch with the switch lever in off position; Fig. 2 is a vertical section of the enclosing box with the circuit interrupting means shown in side elevation therein; Fig. 3 is a fragmentary view similar to Fig. 1 but with the switch lever in the on position, and Fig. 4 is a fragmentary elevation of the locking lugs.

The switch mechanism 1 is of the oscillating snap type with the operating handle 2 pivoted at 3 and projecting through a slot in the box cover. The switch is carried by an insulating base plate 4 secured to the bottom of the box and provided with barriers 5 between the stationary contacts 6 of the respective circuit phases. Mounted on one end of the base plate 4 are thermal cutouts 7 connected to the load terminals 8 and the adjacent switch contacts 6.

The enclosing box is drawn up from sheet steel with its rectangular bottom 9 and side and end walls 10 and 11 integral. The cover 12 is made flat and has a peripheral flange 13 fitting about the open side of the box and is hinged at 14 to the upper end thereof. The upper half of the box is provided with a false front or apron 15 which serves to maintain enclosure of the switch mechanism

1 when the cover 12 is raised to inspect or renew the cutout. This apron is in the form of a substantially flat plate and is held in place by screws 16 engaging lugs on the opposite side walls 10 of the box. A slot 17 is formed in the apron 15 of a size to permit the shank of the switch handle 2 to move back and forth freely therein. A combined shield and locking lever 18 is pivoted at 19 to the inside of the apron. The shield end 20 of the lever is made T-shaped so as to always underlie and shield the slot 17 in whichever position it may be moved by the operating handle 2, the shank 21 of which extends through an aperture 22 at the center of the shield end 20. The outer or locking end 23 of the lever is made L-shaped with an aperture 24 adjacent the angle thereof. It extends through a slot 25 in the right hand side of the box adjacent a bracket or extension 26 secured thereto and having apertures 27 adjacent its ends with the upper one of which the aperture 24 of the lever 18 registers in its extreme off position.

The cover 12 is provided with a bracket 29 corresponding to the bracket 26 on the side of the box and provided with registering apertures 30. When the parts are in the positions indicated in Fig. 1, a padlock 31 may be entered in the upper apertures of the brackets 26 and 29 and the locking lever 18 and thereby lock the switch in off position and the cover from being raised. By inserting the padlock 31 in the lower apertures of the brackets 26 and 29, only the cover will be secured against movement, while the switch is left free to be opened and closed.

With the parts in the positions indicated in Fig. 3, the padlock 31 cannot be entered in the upper apertures of the brackets 26 and 29 because of the bent end of the locking lever 18 being disposed in the path and in consequence whereof it is impossible to lock the switch in the on or closed circuit position.

The operating handle 2 is made with a greater diameter than its shank 21 and the shoulder 32 at the inner end of the handle is located substantially in the plane of the box cover, which has a slot 33 corresponding to slot 17 in the apron and a relatively large opening 34 at the lower end thereof whereby the handle may be enabled to clear the cover when the latter is raised provided the handle be in the depressed or in the open switch position.

sition. Should, however, the handle be raised out of its extreme off position, the sides of the slot 33 will abut the shoulder 32 of the handle and prevent the lid being raised.

In order to render the switch more readily adaptable to stacking in storage and shipping the handle 2 is made disconnectable from its shank and this is accomplished by 10 means of a set screw 35 located in a countersunk hole in the handle and engaging a tapped hole in the shank 21, and to prevent swiveling of the handle thereon, it is provided at its inner end with a tongue 36 and 15 the shank with a corresponding groove 37.

While we have shown and described the best embodiment of the invention known to us, we do not desire to be restricted thereto.

What we claim as new and desire to secure 20 by Letters Patent of the United States, is:—

1. A safety switch comprising a pivotal switch mechanism, its contacts and thermal cut-out means, an open sided protective enclosure about said switch mechanism, its contacts and said cut-out means, an apron fixedly secured over the portion of the enclosure occupied by said switch mechanism and its contacts and provided with a slot for the free movement therein of the operating 25 30 means of said switch mechanism, and a cover for the open side of said enclosure hinged to a wall thereof to swing into full open relation therewith and provided with a slot corresponding to the slot in said apron and having an enlarged opening at one end of its

slot to permit passage of the switch operating means therethrough during opening and closing movements of said cover.

2. A safety switch comprising a switch having a pivoted operating handle, cutout means, an open sided protective enclosure therefor, an apron secured across the open side of said enclosure and provided with a slot for the reception of said switch handle, a combined slot shield and locking lever pivoted upon said apron, a hinged cover for the open side of said enclosure, and pierced padlock extensions on said enclosure and on said cover adjacent the locking end of said lever. 40 45

3. A safety switch comprising a switch having a pivoted operating handle, cutout means, an open sided protective enclosure therefor, an apron fixed to said enclosure over the said switch and provided with a guide slot for said switch handle, a combined slot shield and locking lever pivoted upon said apron and adapted to engage said switch handle at one end and to extend through the side wall of said enclosure at the other, a cover for the open side of said enclosure hinged thereto, padlock extensions on said cover and said enclosure opposite the projecting end of said lever, said lever and said extensions having apertures adapted to register only when the switch is moved into 50 55 60 65 off position.

In witness whereof, we have hereunto set our hands this 21st day of June, 1923.

OTTO H. VAN AMBURG.
LESLIE A. KEMPTON.
